CLAIM

The ornamental design for a machine tool robot as shown and described.

DESCRIPTION

FIG. 1 is a front top perspective view of a machine tool robot, showing my new design.

FIG. 2 is a rear bottom perspective view thereof.

FIG. 3 is front elevation view thereof.

FIG. 4 is a rear elevation view thereof.

FIG. 5 is a right side elevation view thereof.

FIG. 6 is a left side elevation view thereof.

FIG. 7 is a top plan view thereof; and,

FIG. 8 is a bottom plan view thereof.

The dash-dot-dash lines indicate the boundary of the claimed portion beyond which no claim is made. The dash-dot lines indicate portions that form no part of the claimed design. No claim is made to portions that are not shown.
